UNITED STATES PATENT OFFICE.

WILLIAM H. COLLIER, OF NASHVILLE, TENNESSEE.

CONCEALED-HINGE CONSTRUCTION FOR DOORS, &c.

1,221,684.

Specification of Letters Patent.

Patented Apr. 3, 1917.

Application filed May 29, 1916. Serial No. 100,462.

To all whom it may concern:

Be it known that I, WILLIAM H. COLLIER, a citizen of the United States of America, and a resident of Nashville, in the county 5 of Davidson and State of Tennessee, have invented a certain new and useful Concealed-Hinge Construction for Doors, &c., of which the following is a specification.

My invention relates to improvements in 10 the hinging of doors, particularly the doors of carriages, automobiles, etc., and comprises a construction, wherein the hinges are completely concealed, and do not require mortising into either the door or door-frame, 15 and whereby the door swings in such a manner that, when fully opened, the door passage is not blocked by the edge of the door; and also the construction of the hinge is such that no retaining straps to prevent the 20 door swinging too widely are required. My invention consists in the novel construction of the hinge and in the novel combination thereof with the door and door-frame.

The objects of my invention are to improve 25 the hinging of doors, particularly automobile and carriage doors, to completely conceal the hinge, to avoid occasion for mortising the fixed leaf of the hinge into the door-frame, to avoid projection of the hinge 30 into or from the car body, to avoid blocking of the doorway by the edge of the door, to avoid occasion for the use of retaining straps, and generally to provide a hinge 35 construction which is simple, inexpensive, capable of complete concealment in the closed position of the door, and easy to apply to existing constructions of car bodies.

I will now proceed to describe my invention 40 with reference to the accompanying drawings, and will then point out the novel features in claims:

In said drawings:

Figure 1 shows a fragmentary horizontal section through a portion of an automobile 45 body and door, with the door in closed position, the hinge itself being shown in top view.

Fig. 2 is a similar view except that the door is shown wide open.

Fig. 3 is a perspective elevation of a portion 50 of the door and side of the car, showing the curved hinge-leaves of two hinges constructed in accordance with my invention.

In the drawings, 1 designates the outside 55 member of an automobile body, 2 the out-

side member of one of the automobile doors, 3 the door-post of the car body, 4 one of the upright members of the door-frame, 5 the upholstery of the automobile body, and 6 the upholstery of the door. 60

7 designates the fixed leaf of the hinge, secured, as will be seen, to the rear face of the door-post without mortising. 8 designates the movable leaf of the hinge, the same comprising a member 8^a, which, in the closed 65 position of the door, projects rearwardly or away from the door-post 3, and is provided at its end with a curved portion 8^b, curved preferably in substantially the arc of a circle, the angle subtended by the curved portion being preferably about 90°; and beyond this curved portion there is a straight portion 8^c substantially parallel with the portion 8^a, and extending past and beyond the door-post and secured to the door-frame 70 member 4. The two hinge-leaves are, of course, pivotally connected. Preferably, but not necessarily, I provide a fixed shield 9 secured to the door-post 3 outside of the straight portion 8^c of the hinge, which shield 80 guards the hinge cavity, preventing the upholstery of the body from contacting with the hinge.

The door-post 3 is preferably recessed as shown at 10, the door-post having at this 85 point an approximately circular curvature of an angle of about 90°.

As will be seen by comparison of Fig. 1 with Fig. 2, when the door is swung open, the movable hinge leaf 8, swings through 90 the recess 10 in the door-post 3, the curved portion 8^b of such leaf swinging around the curved portion of the door-post, without rubbing thereagainst, and the door, in swinging out, swings back sufficiently to 95 leave the door-way substantially unobstructed by the edge of the door. When the door is wide open, contact of this curved portion 8^b of the hinge leaf 8 with the flange 1^a of the car body, or contact 100 of the curved portion of the hinge leaf with the curved portion of the door-post 3, prevents further swinging of the door, the hinge leaf performing the function of the usual retaining strap to prevent the door 105 from swinging outward too widely. As so-called touring, and also closed, bodies of most present day automobiles, are constructed, the rear doors, if allowed to swing outward more than about 90° will strike 110

the fenders or battery boxes or tool boxes, and hence it is desirable to limit the angle of swing of such doors.

It will be seen that the hinge is completely inclosed and concealed; car upholstery is usually of such depth as to afford ample room for the hinge without the projection of any portion of the hinge beyond the inner line of the upholstery. Such complete concealment and inclosure of the hinge is made possible by the use of a swinging hinge leaf having the straight portion 8^a and the curved portion 8^b terminating in another straight portion 8^c; also by the forming of the door-post 3 (as by the cutting of the recess 10 therein) to provide clearance for the swinging hinge leaf 8.

In certain of the following claims, that side of the door post 3 to which the fixed hinge leaf 7 is shown secured, is referred to as the "rear face" of the door post; the opposite face of such door post is referred to as the "front face" thereof; while the side of the door post against which the member 8^c of the hinge is shown lying, in Fig. 1, is referred to as the "outside face." These terms are used without any reference to what may be the front and what may be the rear of the vehicle of which the door post forms a part.

What I claim is:

1. The combination with a door-frame and door-post, of a hinge comprising a fixed leaf secured to the door-post, and a movable leaf hinged to the fixed leaf and having a portion extending away from the door-frame in the closed position of the door and merging into a curved portion adapted to swing around and close to the door-post as the door opens, such curved portion of the hinge leaf merging into a further portion extending past and close to the door post, and secured to the door-frame.

2. The combination with a door-frame and door-post, of a hinge comprising a fixed leaf secured to the door-post, and a movable leaf hinged to the fixed leaf and having a portion extending away from the door-frame in the closed position of the door and merging into a curved portion adapted to swing around and close to the door-post as the door opens, such curved portion of the hinge leaf merging into a further portion extending past and close to the door post, and secured to the door-frame, said door-post having a recess providing clearance for the swing of such movable leaf.

3. The combination with a door-frame and door-post, of a hinge comprising a fixed leaf secured to the door-post and a movable leaf hinged to the fixed leaf and having a portion extending away from the door-frame in the closed position of the door, and merging into a substantially circularly curved portion subtending an angle of approximately

ninety degrees, and adapted to swing around and close to the door-post as the door opens, such curved portion of the hinge leaf merging into a further straight portion extending past the door post in a direction substantially parallel to the door and secured to the door-frame.

4. The combination with a door-frame and door-post, of a hinge comprising a fixed leaf secured to the door-post and a movable leaf hinged to the fixed leaf and having a portion extending away from the door-frame in the closed position of the door, and merging into a substantially circularly curved portion subtending an angle of approximately ninety degrees, and adapted to swing around and close to the door-post as the door opens, such curved portion of the hinge leaf merging into a further straight portion extending past the door-post in a direction substantially parallel to the door and secured to the door-frame, the door-frame being approximately circularly curved where said movable hinge leaf swings about it, to provide clearance for the swing of that leaf.

5. The combination with a door-frame and door-post, of a hinge comprising a fixed leaf secured to the door-post, and a movable leaf hinged to the fixed leaf and having a portion extending away from the door-frame in the closed position of the door and merging into a curved portion adapted to swing around and close to the door-post as the door opens, such curved portion of the hinge leaf merging into a further portion extending past and close to the door-post, and secured to the door-frame, and a fixed shield inclosing the curved portion of such swinging hinge leaf.

6. The combination with an automobile body or the like, having a door frame and a door post and an upholstery space, of a hinge comprising a fixed leaf secured to said door post, and a movable leaf hinged to the fixed leaf and having a portion extending rearward from the door frame and door post in the closed position of the door and merging into a curved portion adapted to swing around and close to the door post as the door opens, such curved portion of the hinge leaf merging into a further straight portion, the point of merger being near the meeting edge of the rear and outside faces of the door post in the closed position of the hinge, such further extending portion of the hinge leaf extending past and beyond the outside face of the door post in the closed position of the hinge, the said curved portion of the hinge located entirely within said upholstery space in the closed position of the hinge.

7. The combination with an automobile body or the like, having a door frame and door post and an upholstery space, of a hinge comprising a fixed leaf secured to said

door post, and a movable leaf hinged to the fixed leaf and having a portion which, in the closed position of the hinge, extends from the door post into the upholstery space and merges into a curved portion also then located in such upholstery space, such curved portion merging into a further portion secured to the door frame, the curved portion of the movable hinge leaf being adapted to 10 swing about the door post and being con-

structed to so swing without projecting into the body beyond the said upholstery space.

In testimony whereof I have signed this specification in the presence of two subscribing witnesses.

WILLIAM H. COLLIER.
